BRASSIERE

Charles M. Sachs, Fort Lee, N.J., assignor to International Latex Corporation, Dover, Del., a corporation of Delaware

Filed Apr. 3, 1963, Ser. No. 74,280

Term of patent 14 years

(Cl. D20—4)

The figure is a fragmentary plan view of a brassiere showing my new design.

The brassiere has been shown broken away for convenience of illustration. The portion of the brassiere not shown is conventional. The essential features of my design reside in the solid line disclosure on the drawing, namely, in the stitched pattern below the pockets in combination with the scalloped edging.

I claim:

The ornamental design for a brassiere, as shown and described.
